Primary Examiner — Karen E Eldridge Powers(74) *Attorney, Agent, or Firm* — Pillsbury Winthrop Shaw Pittman LLP(57) **CLAIM**

The ornamental design for a rolling container assembly, as shown and described.

DESCRIPTION

FIG. 1 is a perspective isometric view according to my design;

FIG. 2 is a front elevation view of the design of FIG. 1;

FIG. 3 is a rear elevation view of the design of FIG. 1;

FIG. 4 is a left side elevation view of the design of FIG. 1;

FIG. 5 is a right side elevation view of the design of FIG. 1;

FIG. 6 is a top plan view of the design of FIG. 1; and,

FIG. 7 is a bottom plan view of the design of FIG. 1.

The broken lines shown in the drawings illustrate features of the article to which the design is applied that form no part of the claim.
